Attorney

UNITED STATES PATENT OFFICE.

JOHN D. ROBERTS, OF ST. PAUL, MINNESOTA.

TANK.

1,278,018.

Specification of Letters Patent. Patented Sept. 3, 1918.

Application filed March 20, 1917. Serial No. 156,018.

To all whom it may concern:

Be it known that I, JOHN D. ROBERTS, a citizen of the United States, residing at St. Paul, in the county of Ramsey and State of Minnesota, have invented a new and useful Improvement in Tanks, of which the following is a specification.

This invention relates to that class of tanks, which is generally although not necessarily employed for heating water by steam or other heating medium, the primary object being to provide a simple and durable tank which is inexpensive in construction and effective in use. With tanks of this character the construction is usually complicated and the parts collect scale and sediment, which is very difficult to remove and which renders the tank inefficient and objectionable, the tank itself soon deteriorating and leaking. By the use of my invention these objections are substantially overcome, the tank being extremely simple in construction and reducing to a minimum the formation of scale and the collecting of sediment therein.

In the accompanying drawing forming part of this specification, Figure 1 is a longitudinal section of my invention, and Fig. 2 is a section taken on the line X—X of Fig. 1.

In constructing my invention two cylindrical shells 2 and 3 are employed, the former being of larger diameter than the latter and said shells being concentrically arranged one within the other and spaced a short distance apart to produce a jacketing space between them. At one end of the tank structure are two domes or convex shells 4 and 5, which are likewise concentrically arranged, the arc of the inner shell being of less diameter than that of the outer shell and said convex shells being also spaced apart to form a continuation of the jacketing space between the cylindrical shells. The edge of the convex shell 5 is secured in the inner edge of one end of the shell 3 by rivets 6 or other suitable means and the edge of the convex shell 4 is secured in the corresponding end of the cylindrical shell 2 by rivets 7 or other suitable means. The opposite ends of the cylindrical shells to those which are provided with the convex shell members 4 and 5 are supported in spaced parallel relation upon the solid ring 8, which closes the space at the end of the tank structure at one of the ends between the shell mem-

bers 2 and 3 and a concave shell member 9 is secured at its edge which is formed with a flange 10 to the inner edge of the corresponding end of the shell member 3 by means of rivets 11 or other suitable means which also secure the shells 2 and 3 and ring 8 tightly together to produce a leak proof joint.

The concave shell member 9 closes the end of the inner shell 3 opposite that which is provided with the convex shell member 5. In this manner a hot water chamber A is formed by the cylindrical shell member 3 and inner end members 5 and 9 and an outer jacket space B is provided surrounding the hot water chamber. The ends of the cylindrical members 2 and 3 are held in spaced relation adjoining the convex members 4 and 5 by means of sectors 12 made of angle members secured to one of the cylindrical shell members by rivets 13 or other suitable means, said sectors being spaced apart between their ends, so that steam or other heating medium may circulate freely from one side to the other.

Water to be heated is admitted into the lower portion of the hot water chamber A through a pipe or duct 14 which passes through the outer shell 2 and is threaded or otherwise secured to the inner shell, a gland 15 being provided in the outer shell surrounding said duct to produce a tight joint. The water which is admitted after being heated is conducted from the water chamber A by the pipe or duct 16, which likewise passes through the outer shell 2 and is threaded in the inner shell, a gland 17 being provided on said outer shell through which said duct passes and by which a tight joint is produced. This outlet duct is preferably arranged at a distance from the inlet duct 14 and leading from the upper portion of the water chamber A. Disposed longitudinally in the water chamber and interposed between the ducts 14 and 16 is a baffle 18, which as illustrated is a wall or plate curved downwardly between its side edges and secured to the walls of the inner shell 3 and concave shell 9 by rivets 19 or other suitable means.

Live steam is admitted into the steam jacket space by means of one or more steam pipes or ducts 21, which are tapped into the outer shell 2 near the upper portion of the jacket space. After circulating through the steam jacket space, the steam and water of

condensation is conducted away by the egress duct 20 in the outer casing. As a result of this structure, a large heat radiating surface is provided for heating the body of water 5 in the tank, said surface being smooth in contour and being free of a large number of sharp bends and turns, which would naturally tend to collect scale and sediment. The structure shown is adapted particularly for 10 horizontal use, but the arrangement of the parts may be easily adapted for use when the cylindrical shell members are placed in vertical instead of horizontal position.

The inner central portion of the concave 15 shell member 9 is shown provided with a clean out door or stopper 22 of usual construction which can easily be removed when it is desired to gain access into the water chamber A.

20 In accordance with the patent statutes I have described the principles of operation of my invention together with the apparatus which I now consider to represent the best embodiment thereof, but I desire to have it 25 understood that the construction shown is only illustrative, and that the invention can be carried out by other means and applied to uses other than those above set forth within the scope of the following claim.

30 Having described my invention what I

claim as new and desire to protect by Letters Patent is:—

A tank, comprising, in combination, a pair of outer and inner cylindrical shells spaced apart to assist in producing an outer heating 35 medium jacket space and an inner liquid holding chamber, inner and outer end members spaced apart and secured to said cylindrical member to form a continuation of said jacket space near one end of said structure, 40 a spacing ring interposed between the ends of said cylindrical shells near the opposite end of said structure from said end members, a single end shell in the inner shell member having its edge disposed within said 45 ring, means for securing said cylindrical and single shells and ring together, said jacket space being provided with ingress and egress heating medium ports, and said liquid holding chamber having ingress and 50 egress ports, a baffle in said inner shell disposed between the liquid holding chamber ingress and egress ports, and spacing means interposed between said outer and inner cylindrical shell formed with openings for the 55 heating medium circulating through said jacket space.

In testimony whereof, I have signed my name to this specification.

JOHN D. ROBERTS.
